GUN SIGHT

Stanley J. Kwako, 1001 Hannifin St.,
Bismarck, N. Dak. 58501

Filed Sept. 28, 1972, Ser. No. 294,928

Term of patent 14 years

Int. Cl. D22—01

U.S. Cl. D22—8

FIG. 1

FIG. 2

FIG. 3

FIG. 4

FIG. 5

FIG. 6

FIG. 7

FIG. 8

FIG. 9

FIG. 10

FIG. 1 is a perspective view of a first embodiment of my invention of a gun sight adapted for placement on a double barreled gun such as a double barreled shotgun.

FIG. 2 is a front elevation view of the gun sight of FIG. 1, the back side being substantially identical.

FIG. 3 is a side elevation view of the gun sight of FIG. 1, the other side being substantially identical.

FIG. 4 is a top view of the gun sight of FIG. 1.

FIG. 5 is a bottom view of the gun sight of FIG. 1.

FIG. 6 is a perspective view of a second embodiment of my invention of a gun sight adapted for placement on a single barreled gun such as a single barreled shotgun.

FIG. 7 is a front elevation view of the gun sight of FIG. 6, the back side being substantially identical.

FIG. 8 is a side elevation view of the gun sight of FIG. 6, the other side being substantially identical.

FIG. 9 is a top view of the gun sight of FIG. 6.

FIG. 10 is a bottom view of the gun sight of FIG. 6.

I claim:

The ornamental design for a gun sight, as shown.
